UNITED STATES PATENT OFFICE

161,102

SHOE HEEL

Francis Nicholas Grasberger, Lynchburg, Va.

Application June 1, 1949, Serial No. 2,984

Term of patent 14 years

(Cl. D7—5)

To all whom it may concern:

Be it known that I, Francis Nicholas Grasberger, a citizen of the United States, residing at Lynchburg, county of Campbell, State of Virginia, have invented a new, original, and ornamental Design for a Shoe Heel, of which the following is a specification, reference being had to the accompanying drawing, forming part thereof.

Figure 1 is a side elevational view of a shoe heel, showing my new design;

Fig. 2 is a side elevational view of the opposite side of the shoe heel shown in Fig. 1;

Fig. 3 is a bottom plan view of the shoe heel shown in Fig. 1; and

Fig. 4 is a front elevational view of the shoe heel shown in Fig. 1.

My design for a shoe heel of the wedge type is characterized by a raised inner arcuate portion as shown in Figures 1 and 2, the inner peripheral

portion of the arcuate formation being higher than the outer peripheral portion thereof.

I claim:

The ornamental design for a shoe heel, as shown and described.

FRANCIS NICHOLAS GRASBERGER.
